FOOD GRINDER

Ralph N. Kircher and Leonard E. Finch, West Bend, Wis., assignors to West Bend Aluminum Co., West Bend, Wis., a corporation of Wisconsin

Application October 12, 1949, Serial No. 5,460

Term of patent 14 years

(Cl. D89—1)

To all whom it may concern:

Be it known that we, Ralph N. Kircher and Leonard E. Finch, both citizens of the United States, residing at West Bend, in the county of Washington and State of Wisconsin, have invented a new, original, and ornamental Design for a Food Grinder, of which the following is a specification, reference being had to the accompanying drawing, forming a part thereof, and in which:

Fig. 1 is a side elevation of a food grinder showing our new design;

Fig. 2 is a rear elevation; and

Fig. 3 is a perspective view.

The characteristic features of the design reside in the portion shown in full lines.

We claim:

The ornamental design for a food grinder, as shown and described.

RALPH N. KIRCHER.
LEONARD E. FINCH.
